(57) **CLAIM**

The ornamental design for lawn mower wheel unit assembly, as shown and described.

DESCRIPTION

FIG. 1 is a first perspective view of a lawn mower wheel showing my new design;
FIG. 2 is a second perspective view thereof;
FIG. 3 is a front view of FIG. 1;
FIG. 4 is a rear view of FIG. 1;
FIG. 5 is a left side view of FIG. 1;
FIG. 6 is a right side view of FIG. 1;
FIG. 7 is a top plan view of FIG. 1;
FIG. 8 is a bottom plan view of FIG. 1; and,
FIG. 9 is a perspective view of the usage status thereof.
The broken line showing on the surface of the claim is included for the purpose of illustrating portions of the lawn mower wheel assembly and forms no part of the claimed design. The broken line showing of the string trimmer in FIG. 9 is included for environmental purposes only and forms no part of the claimed design.

1 Claim, 9 Drawing Sheets
